UNITED STATES PATENT OFFICE.

CHARLES L. HUDLER, OF ST. LOUIS, MISSOURI.

HYDROAEROPLANE.

1,268,779.

Specification of Letters Patent. Patented June 4, 1918.

Application filed July 24, 1917. Serial No. 182,517.

To all whom it may concern:

Be it known that I, CHARLES L. HUDLER, a citizen of the United States, residing at St. Louis, in the State of Missouri, have invented a new and useful Hydroaeroplane, of which the following is a specification.

This invention relates to hydroaeroplanes, one of the objects of the invention being to utilize a series of superimposed sustaining planes of the minimum width from the front to rear and which are rigidly supported or connected relative to the car of the machine by the use of trusses constructed and arranged in a novel manner.

15 A further object is to provide a cellular sustaining body offering the minimum wind resistance and which can be made entirely or partly of metal if desired.

20 A still further object is to provide a machine of this character which will automatically maintain its lateral balance and which can be controlled readily in its flight.

25 With the foregoing and other objects in view, which will appear as the description 25 proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

30 In the accompanying drawings the preferred form of the invention has been shown.

35 In said drawings:—

Figure 1 is a front elevation of a multiple plane hydro-aeroplane embodying the present improvements.

40 Fig. 2 is a plan view, one side portion being broken away.

Fig. 3 is a side elevation of the machine.

45 Fig. 4 is an enlarged front elevation of the tension means used to take up slack in the connections between the connecting frame and the guys.

Fig. 5 is a section on line 5—5 Fig. 4.

Fig. 6 is an enlarged vertical section taken from front to rear through two of the sustaining planes.

50 Fig. 7 is a section on line 7—7 Fig. 6.

Fig. 8 is an enlarged section on line 8—8 Fig. 2.

55 Fig. 9 is a detail view of a portion of one form of truss which may be used in the construction of the machine.

Fig. 10 is a section on line 10—10 Fig. 9. Fig. 11 is a section through a modified form of sustaining plane.

55 Fig. 12 is a detail view of another modified form of truss.

Fig. 13 is a section through a modified form of sustaining plane.

Referring to the figures by characters of reference, 1 designates an elongated truss spar made up of upper and lower strips of thin steel or other metal placed edge to the wind and which are spaced apart but connected by crossed strips 2 which can, if desired, be assembled as shown in Figs. 9 and 10, the various parts being secured together by solder or in any other manner desired. Mounted on the middle portion of this spar 1 is the boat like body 3 of the machine and suitably connected to the spar beyond the sides of this body are supporting wheels 4 which can be 75 in the form of casters or can be constructed in any other manner desired. Pontoon 5 are mounted on the spar 1 beyond the sides of the body 3 and braces 6 are used for holding the body 3 and the pontoons 5 fixed 80 relative to the spar.

Erected on the spar 1 and straddling the body 3 is a mast 7 formed of upwardly converging truss spars which can be of the same construction as the spar 1 and are 85 placed with the edges of the metal strips to the wind. The upper end of each of these upwardly converging spars is compressed to form an upwardly projecting stem 8 and fixedly mounted on the lower 90 portion of this stem is a head 9 in the end portions of which are mounted adjusting bolts 10. These bolts are threaded into slides 11 which engage and move along the stem 8 and project in opposite directions 95 therefrom as indicated particularly in Fig. 5. Each slide has a slot 12.

Extending forwardly from the stem 8 and above the head 9 is a stabilizing plane 13 preferably corrugated from its lower to its upper edge as shown in Fig. 1 thereby to impart a stiffness to the plane in the direction of its length. This plane is extended forwardly from the stem 8 while extending rearwardly from the stem and hingedly connected thereto is an aileron 14. Connected to the sides of this aileron are actuating cords 15 which are extended over suitably arranged guides 16 and downwardly to points within the body 3 where they can be 110

conveniently grasped and actuated by the aviator.

Connected to and extending laterally from the upper portion of the mast 7 is a truss 5 spar 17 which may be similar in construction to the spars 1 and 7 and with the strips constituting said spar placed with their edges to the wind. The spar 17 is not straight from end to end but is bent at its center so 10 that said spar will extend upwardly and outwardly from a point midway between the spars of the mast 7, the outer ends of the spar 17 being substantially in vertical alignment with the outer ends of the spar 1.

15 Secured to the spars 1 and 17 are parallel normally vertical tie strips 18 formed of narrow flat metal strips placed edge to the wind. The upper portions of these tie strips, may be provided above the bar 17, with guy 20 wires which are extended along converging lines to the upper portion of the mast 7 where they are projected into and soldered or otherwise secured within the slots 12 in the slides 11. These converging portions or 25 guys have been indicated at 19. By providing this arrangement it will be apparent that when the slides 11 are adjusted toward the head 9 by means of the bolts 10, the converging strips 19 will be drawn taut and 30 likewise draw taut the tie strips 18 between the spars 1 and 17. Additional tie strips 20 may be interposed between and parallel with the tie strips 18 and, like the strips 18, placed with their front edges to the wind so 35 that these strips 18 and 20 can thus cut freely through the air.

Erected on the front portion of the body 3 is a frame 21 made up of upwardly converging truss beams constructed in the same 40 manner as the spars 1 and 17 and constituting a support for the shaft 22 of a propeller 23, this shaft receiving motion through any suitable mechanism indicated generally at 24 from a motor 25 carried by the body 3.

45 Arranged below the spar 17 and parallel with it are superposed sustaining planes 26 which are relatively narrow from front to rear but which extend throughout the length of the spar 17 and are arranged one directly 50 above the other as shown particularly in Fig. 3. These sustaining planes can be made of flat strips of metal made very thin and as shown in Figs. 6 and 7, said strip being attached to the tie strips 18 and 20 by angle 55 strips 27 or in any other suitable manner. Or, if preferred, each of the sustaining planes can describe an elongated ogee curve as indicated at 28 in Fig. 11, the front portion of each plane being inclined upwardly 60 and forwardly at a slight angle while the rear portion is inclined downwardly and rearwardly.

Mounted on the rear portion of the body 3 is an upwardly and rearwardly inclined truss 65 frame 29 similar to the truss frame 21 and

having the edges of its various strips arranged so as to cut through the air. The upper portion of this frame 29 has a pivot shaft 30 extended rearwardly therefrom, said shaft being extended through a truss frame 31 which 70 likewise may be constructed as shown in Fig. 9 and as shown at 1 and 17 in Fig. 1. Extending laterally from this truss frame and forwardly and rearwardly therefrom are superposed planes 32 connected by vertical planes 33 which coöperate with the planes 32 thus to form a cellular tail plane. As the tail planes are adapted to rotate upon the shaft 30 and said shaft is adapted to swing laterally, thus by connecting controlling 75 cords 34 to the top, bottom and sides of the tail plane, the said tail plane can be swung upwardly or downwardly and to either side thus to elevate, lower and horizontally steer the machine.

80 As shown in Fig. 3, guys 35 can be extended from the front and rear portions of the body 3 upwardly to the top of the mast 7 thus to steady the mast and hold it rigid relative to the body 3.

85 It is a well settled fact that the first six inches or more of the surface of a sustaining plane is the most effective portion of the plane in the displacement of the air and with this principle in mind the present machine has been devised, the same using sustaining planes which are relatively narrow from front to rear but which are of the same efficiency practically as ordinary planes of the same breadth. By superposing the planes as shown in Figs. 1 and 3 a 90 greatly increased lifting power is obtained because the lifting surface and consequent downward displacement of air is materially increased. By having the planes braced and connected by the vertical parallel strips a very rigid structure is obtained and the sustaining planes can be set at the desired angle to effect an ascent or descent, by 95 tilting the tail plane. By having the sustaining planes extended along upwardly diverging lines, the machine, if tilted, will produce an increasing displacement on the lower side until the planes at that side reach horizontal positions. The downward displacement 100 at the other side of the machine will be proportionately diminished so that the machine will thus automatically be restored to its point of equilibrium. This lateral tilting will furthermore be offset by the stabilizing 105 plane 13 and, should the machine be tilted to a dangerous extent toward one side, the aileron 14 can be shifted toward said side thus to prevent an increased opposition to the flight and cause the machine to swing bodily 110 back to its upright position. A structure when made as described can be formed entirely of metal, the sustaining planes, the trusses and the spacing and tying strips all 115 being formed of thin flat pieces of metal. 120 125 130

Obviously, however, if desired, the planes can be made of canvas or other fabric. Furthermore the construction of the trusses can be changed, it merely being necessary to so make them that the strips constituting the trusses will present their edges to the wind, thus to cut through the air and to allow the air to circulate freely through the trusses. When trusses are thus made and arranged 10 they offer the minimum resistance to the forward movement of the machine.

As shown in Fig. 12 each truss can be made of two parallel strips 36 and a single interposed side strip 37 arranged in zig-zag 15 form. Various other arrangements of the parts can be provided to meet different conditions or requirements.

In Fig. 13 a modified form of sustaining plane has been illustrated. In this form of 20 device the body of the plane is formed of canvas or other fabric stretched between two truss spars, the canvas body being indicated at 38 while the truss spars are indicated at 39 and 40. These two spars are arranged at 25 different levels so that the canvas body can be attached to bottom of one of them and to the top of the other. The two spars may be connected by an angle strip 41 or in any other suitable manner. This construction of 30 sustaining plane can be utilized whenever it is desired to employ canvas instead of metal planes.

What is claimed is:—

1. A flying machine including a transverse 35 spar comprising a truss made up of upper and lower flat strips and interposed connected flat strips, all of the strips being adapted to cut through the air, a superstructure upon the truss made up of thin strips 40 connected together and adapted to cut through the air during the forward movement of the machine, and superposed sustaining planes carried by the superstructure.

2. A flying machine including upper and 45 lower spars, a mast connecting and projecting above the spars, said spars and mast each comprising parallel flat metal strips and interposed connecting flat strips, said strips coöperating to form trusses and all 50 of the strips being arranged to cut through the air during the forward movement of the machine, flat tie strips placed with their front edges to the wind and connecting the upper and lower spars, and superposed sustaining planes connected to the tie strips 55 and between the spars.

3. A flying machine including upper and lower spars, a mast connecting and projecting above the spars, said spars and mast 60 each comprising parallel flat metal strips and interposed connecting flat strips, said strips coöperating to form trusses and all of the strips being arranged to cut through the air during the forward movement of the 65 machine, flat tie strips placed with their

front edges to the wind and connecting the upper and lower spars, and superposed sustaining planes connected to the tie strips and between the spars, said sustaining planes diverging upwardly along straight 70 lines.

4. A flying machine including upper and lower spars, a mast connecting and projecting above the spars, said spars and mast each comprising parallel flat metal strips 75 and interposed connecting flat strips, said strips coöperating to form trusses and all of the strips being arranged to cut through the air during the forward movement of the machine, flat tie strips placed with their front edges to the wind and connecting the upper and lower spars, and superposed sustaining planes connected to the tie strips and between the spars, said sustaining planes diverging upwardly along straight 80 lines, guys extending from the upper spar to the upper portion of the mast, and means for taking up the slack within the guys.

5. A flying machine including upper and lower spars, a mast connecting and projecting above the spars, said spars and mast 90 each comprising parallel flat metal strips and an interposed connecting flat strip, said strips coöperating to form trusses and all of the strips being arranged to cut through 95 the air during the forward movement of the machine, flat tie strips placed with their front edges to the wind and connecting the upper and lower spars, and superposed sustaining planes connected to the tie strips 100 and between the spars, said sustaining planes diverging upwardly along straight lines, guys extending from the upper spar to the upper portion of the mast, and means for taking up slack within the guys, a 105 stabilizing plane upstanding from the mast and extending longitudinally of the machine, and an aileron hingedly connected to and adapted to swing laterally relative to the stabilizing plane.

6. A flying machine including upper and lower spars, a mast connecting and extending above the spars, said spars and mast each consisting of parallel flat strips, connecting flat strips interposed between said 115 parallel strips and coöperating therewith to form a truss, the front edges of the strips being extended in the direction of the line of flight, superposed sustaining planes interposed between the spars, and extending in 120 opposite direction from the mast the planes at the two sides of the mast diverging upwardly along straight lines, a body rigidly mounted on the lowest bar and straddled by the mast, a cellular tail plane movably connected to the rear portion of the body, and means for shifting the tail plane upwardly, downwardly and laterally to control the direction of flight.

7. A flying machine including upper and 125

lower spars, a mast connecting and extending above the spars, said spars and mast each consisting of parallel flat strips, a connecting flat strip interposed between 5 said parallel strips and coöperating therewith to form a truss, the front edges of the strips being extended in a direction of the line of flight, superposed sustaining planes interposed between the spars, and extending 10 in opposite direction from the mast, the planes at the two sides of the mast diverging upwardly along straight lines, a body rigidly mounted on the lower bar and straddled by the mast, a cellular tail plane mov- 15 ably connected to the rear portion of the body, and means for shifting the tail plane upwardly, downwardly and laterally to control the direction of the flight, a stabilizing plane extending vertically above the mast 20 and fixed relative thereto, an aileron hingedly connected to said plane and movable about a vertical axis, and means for shifting the aileron.

8. A flying machine including upper and lower spars extending transversely of the 25 line of flight, a mast connecting the spars, said mast and the spars each consisting of flat metal strips placed edge to the wind and assembled to form trusses and upwardly and outwardly diverging series of sustain- 30 ing planes extending in opposite directions from the mast and between the spars, said planes being superposed and each plane defining an elongated ogee curve extending downwardly from front to rear. 35

9. A flying machine including flat metal strips placed edge to the wind and as- 35 sembled to form connected trusses, and a sustaining plane connected to these trusses and defining an ogee curve extending down- 40 wardly from front to rear.

In testimony that I claim the foregoing as my own, I have hereto affixed my signature.

CHARLES L. HUDLER.
